UNITED STATES PATENT OFFICE

HARRY F. SMITH, OF DAYTON, OHIO, ASSIGNOR TO THE GAS RESEARCH COMPANY, OF DAYTON, OHIO, A CORPORATION OF OHIO

GAS PRODUCER

Application filed June 26, 1922. Serial No. 570,972.

This invention relates to gas generation, and more particularly to the generation of producer gas.

One of the principal objects of the invention is to provide an improved method of gas generation, and apparatus for carrying that method into effect, in which the time of the blowing up period is materially shortened, the character of the generated gas is improved 10 and maintained more uniform, and the expense of operating and maintaining the apparatus materially decreased.

Another object of the invention is to provide a gas producer, of that character in 15 which part of the fuel within the generating chamber functions as a lining for that chamber, with means for preventing undue lateral spread of the blast along the base of the gas producer which supports the fuel bed.

Another object of the invention is to provide a producer, with a saturator located to receive heat, for vaporizing the water therein, from the active portion of the fuel bed and also from the offgoing gases, which is so constructed that, for a given load, there is a 20 substantially constant heat input into the saturator despite fluctuations in the relative quantities of heat input from the active zone of the fuel bed and from the off-going gases.

Another object of the invention is to provide a saturator of this character which is so constructed as to automatically vary the quantity of moisture available for saturation of the blast to accord with variations in load.

Still another object of the invention is to provide a grate which is so constructed as to remove ashes, clinker, and the like, with minimum unnecessary agitation of the fuel bed.

Generally, the object of this invention is to 40 provide a gas producer which is so constructed as to minimize heat losses from the active zone of the fuel bed; to control the saturation; to concentrate the blast and prevent undue lateral spread thereof, and thus eliminate wall action; to provide means for satisfactorily removing ash, clinker and the like, from the generating chamber; to thus give a producer requiring a very short blowing up period, that is one which is quick starting, 45 which is adapted to operate continuously over

long periods of time, which during such operation will generate a gas of good quality, and which is flexible in its operation, so as to have a wide range of load.

Other objects and advantages of the invention will be apparent from the description set out below when taken in connection with the accompanying drawing.

As set out in the copending application of Harry F. Smith No. 515,861 filed November 17, 1921, now Patent 1,772,642, dated August 12, 1930, it is the very general practice in the gas producer art to provide the generating chamber of the gas producer with a heat resisting and heat insulating lining, which serves to both cut down radiation losses from the active fuel bed and to prevent the metallic shell of the producer from being unduly heated. This lining usually consists of fire-brick, the lining ordinarily varying in thickness, in the producers in general use, from six to twelve inches, and at times even more. Sometimes the fire brick lining is dispensed with and a water cooled shell for the generating chamber provided. In producers as heretofore used commercially, which generally run from three to fourteen feet in internal diameter, the ratio between the mass of incandescent fuel within the active fuel bed and the radiating surface of the producer shell is such that, with a lining of the kind specified, the heat losses, due to radiation, are comparatively so small that they occasion no serious trouble in the operation of the producer.

The blowing up period, though of considerable duration, perhaps as much as one-half to three-quarters of an hour, or even more, is not objectionable since the producer is ordinarily brought up to good gas making conditions before there is any appreciable demand for the generated gas. And the heat losses during operation of the producer are not sufficient to seriously interfere with the gas making reactions. Still this heat loss does affect the efficiency of the gas making reactions, and in addition affects the quality of gas produced. For the higher the heat losses the greater will generally be the percentage of non-combustible constituents.

in the generated gas. Therefore, any decrease in the relative proportion of heat lost by radiation results in a corresponding increase in efficiency of the apparatus.

5 While the radiation losses in producers of the kind heretofore generally used may be disregarded, when it is attempted to generate gas in producers of comparatively small size, for example those having a grate diameter of twelve inches, or less, it is found that 10 the percentage of heat thus lost through radiation, tends to increase very rapidly as the diameter of the producer decreases. And if a producer of this small size is provided 15 with a fire brick lining of a thickness corresponding, proportionately, to the thickness of the firebrick lining used in the conventional producer the heat losses will be so great that not only is the blowing up period 20 unduly prolonged, but satisfactory operation of the producer is prevented. Increasing the thickness of the lining, to increase its resistance to transfer of heat therethrough, will cut down the radiation loss, and by providing a suitably thick lining the producer 25 will function satisfactorily to make gas. However, if a firebrick lining of sufficient thickness to cut down radiation losses to a satisfactory degree is provided the heat capacity of this lining is so great that the blowing up period will be unduly prolonged. But such a small size producer will function satisfactorily if it is provided with a lining 30 having sufficient heat insulating capabilities 35 and also having small heat capacity.

A type of producer having a lining of this character is shown in the copending application of Harry F. Smith Serial No. 398,749 filed July 24, 1920. The producer disclosed 40 in that copending application has a lining consisting of a thin inner layer of fire brick, of small heat capacity, backed by a comparatively thick layer of heat insulating material. Such a producer, with a grate of less 45 than six inches diameter, operating upon charcoal, and starting cold, can be brought up to good gas making condition within fifteen minutes, and often in five minutes. But where the gas generated is to operate a 50 gas engine, such as the engine forming the power unit of the well known types of individual house lighting plants, it is especially desirable that the blowing up period be very brief, and that the producer quickly come 55 up to approximately maximum gas making conditions. For the mixing valve, or carbureting device, which controls the air and gas mixture fed to the engine cannot be set for most efficient operation until the gas 60 becomes of approximately uniform character.

But where the conventional type of lining is dispensed with and the entire generating chamber is filled with carbonaceous material, such as charcoal, coke or the like, the blast 65 being so controlled that the active zone of

the fuel bed is at all times surrounded by a layer of inactive fuel which serves to prevent transfer of heat from the incandescent or active zone of the fuel bed to the shell of the producer and radiation from the shell 70 into the surrounding atmosphere, the blowing up or starting period may be greatly decreased, and it is quite exceptional when a starting period of as much as five minutes is required. In fact combustible gas has 75 been secured, operating upon charcoal, with a producer of this general character, within thirty seconds from the time of first igniting some kindling, such as a newspaper, in the ash pit, and an engine operating upon the 80 gas generated in such a producer has been caused to develop approximately maximum power within less than five minutes.

The producer forming the subject matter of this particular invention is quite similar in certain of its underlying fundamentals of construction and in certain of its constructional details to the producers forming the subject matter of the above referred to copending applications; but because of certain features of construction which are incorporated therein, and which are not incorporated in the producer disclosed in the said copending applications, this particular producer is adapted to give more satisfactory 90 operation where it is operated continuously over an extended period of time, and will 95 also generate a better average character of gas over such a continuous period of operation.

The features of construction of the producer embodying this invention are shown in the accompanying drawing, in which like characters of reference designate like parts throughout the several views thereof:

Fig. 1 is a plan view of a power plant comprising, generally, a producer, a purifier, a gas engine constructed to operate upon the gas generated within the producer, and at the same time to furnish the suction for causing the generation of such gas;

Fig. 2 is a sectional view along the line 2—2 of Fig. 1;

Fig. 3 is an enlarged sectional view through the base of the producer shown in Fig. 1, the view being along the line 3—3 of Fig. 1 looking in the direction of the arrows;

Fig. 4 is a sectional view, along another plane, through the base of the producer, this view being along the line 4—4 of Fig. 1;

Fig. 5 is a view partly in vertical section through the blower, and cooperating valve and switch mechanism, which is used in starting up the producer;

Fig. 6 is another view of the blower, valve and switch, this view being also partly in section, the section being along a line at right angles to the plane of the section of Fig. 5;

Fig. 7 is a vertical section through a pro-

ducer having a somewhat modified form of base construction;

5 Fig. 8 is a sectional view through the base of the modification shown in Fig. 7, the view being at substantially right angles to the plane of Fig. 7;

Fig. 9 is a vertical sectional view through still another modified form of producer;

10 Fig. 10 is a plan view of the base section of the producer shown in Fig. 9;

Fig. 11 is a plan view of the base of the form of producer shown in Figs. 1-4;

15 Fig. 12 is a horizontal sectional view showing certain details of construction of the purifier; and

Fig. 13 is a detail view, in the nature of a plan view, of the scraper forming one element of the purifier.

20 As shown in Figs. 1 and 2 the producer constitutes one element of a power plant, but of course it need not necessarily be used as an element in such a system, for it may be used to supply gas for any desired use, as by way of illustration, for industrial heating operations, such as heat treating, drop forging and the like, or for domestic purposes such as the cooking of food, the heating of water, the heating of the rooms of a house, lighting, and the like. But as illustrating a preferred embodiment of the invention it is shown in connection with a gas engine having a generator direct connected thereto and serving to supply electric current for domestic use.

25 The producer, forming a part of the plant disclosed in Figs. 1 and 2, is designated generally by the numeral 20 and comprises a metallic shell 21 and a base portion 22. The metallic shell 21 is preferably of sheet metal, the thickness of which varies according to the size of the producer; but inasmuch as this shell, in the type of producer shown herein, has to sustain little or no weight other than the weight of the shell itself it may be made of comparatively light material. In producers of the small size adapted for serving as a unit in a power plant for domestic house lighting purposes, in which the producer shell may have an over all diameter of 20 to 24 inches and an over all height of 24 to 36 30 inches, a shell made of $\frac{1}{8}$ inch sheet steel has been found to function very satisfactorily. The upper end of the shell is closed by means of a top 23, which is shown as welded in place, although it may be secured in any other desired manner so long as a gas tight joint exists between the top and the shell. This top has an opening 24 therein through which fuel is introduced into the gas generating chamber, this opening being surrounded by 35 an upstanding flange 25. Cooperating with the flange 25 is a cover 26, with which cooperates a locking bail 27. As shown the cover 26 is substantially hemispherical in shape and a correspondingly shaped bail is provided the 40 ends of which are bent to form loops or eyes

which engage upon suitable lugs carried by the members 28, which are in turn secured to the top 23 by some suitable means, such for instance as the bolts 29. The bail when positioned on the lugs is thus capable of free movement into or out of engagement with the cover 26 to release that cover so that it may be readily removed or to hold it in gas-tight contact with the flange 25. A stop 30 is carried by the cover 26 to limit movement of the bail. The cover is provided with a machined surface which is constructed to make a tight joint with the flange 25. If desired the cover may have a groove therein for receiving the flange 25, suitable packing being provided in this groove to make a tight joint.

45 The other end of the metallic shell 21 is open and is adapted to seat upon the base member 22, which is provided with a peripheral groove 32, adapted to receive the free cooperating end of the metallic shell 21, suitable packing material 33 being positioned therein, so that when the shell and base member are drawn tightly together leakage between these two members is prevented. The shell, adjacent its free end is provided with outstanding projections 34 each having a passage therein, adapted for alignment with the cooperating passages in the extensions 35 of the base member. A plurality of legs 36 are 50 provided, for supporting the assembled shell and base member, each of these legs having a threaded extension 37, constructed for positioning within the aligned passages in the members 34 and 35, and to receive a nut 38, proper turning of the nuts 38 resulting in drawing the shell and base member firmly together to hold them rigidly in assembled position, and to, at the same time, hold the supporting legs 36 firmly in position. An upstanding flange 39 is provided upon the base member, which extends a short distance upwardly into the shell 21 when the device is in assembled position, to hold the shell and base member against lateral movement relative to each other, to thus maintain the shell properly centered.

55 The base member 22, when the producer is assembled and in operation, sustains the fuel bed which is contained within the shell 21. This base member is provided centrally with an opening 40 which is surrounded by an upstanding flange 41, which extends upwardly to a height at least as great as the height of the peripherally arranged flange 39, a trough or pocket being thus formed within the base member between these two flanges. During operation this trough contains a layer of heat insulating material, preferably a layer of material consisting of some of the finely divided carbonaceous material which is being used as fuel and which is considerably more finely divided than the bulk of the fuel comprising the fuel bed. Where the producer is operating upon charcoal, for example, this 60

layer of material will consist of charcoal dust, where the producer is operating upon coke, this layer would consist preferably of coke dust or breeze. If desired a layer of ashes 5 may be used, or even a layer of sand, though neither of these two materials functions as satisfactorily as the finely divided fuel. In fact any type of heat insulating material may be used, but preferably the finely divided fuel 10 is used since it has practically all of the desirable characteristics of a material such as ashes or sand, without the undesirable characteristics of fusing which results in clinker formation, and in addition is always available. 15 The purpose of this layer of heat insulating material is to heat insulate the base member from the active zone of the fuel within the shell 21. The opening 40 serves as a blast port, or tuyère, opening into the generating 20 chamber, the blast, which preferably consists of air containing a quantity of moisture, being introduced therethrough into the fuel bed to maintain the active zone of the fuel bed in a state of incandescence, and to cause 25 the gas making reactions to take place. A grate 43, is positioned within the opening 40, which grate is carried by a rotatable shaft 44, which is in turn mounted within a standard 45 supported upon the bottom of the ash pit 20 46 of the base member. This grate is preferably in the form of a spiral or worm, and its construction is such that when the shaft 44 is rotated ashes, clinker, and the like, will be forced downwardly into the ash pit. This 35 grate serves to support the greater part of the active zone of the fuel bed, the blast of air and moisture which is introduced through the port 40 being so controlled as to pass only through the central portion of the fuel bed, thus leaving a zone of inactive fuel about this 40 central or active portion of the fuel bed which serves to heat insulate the active zone of the fuel bed from the metallic shell and to thus prevent heat losses from the incandescent fuel 45 to the atmosphere.

The desired control of the blast is secured, primarily, by properly positioning the gas offtake. The producer of course may be either pressure operated or suction operated, 50 but in either case the blast as it passes through the fuel bed will follow the path of least resistance. With a fuel bed of substantially uniform resistance to draft therethrough, this path of least resistance will normally be the 55 shortest distance between the point of blast inlet, which is the opening 40, and the point of outlet which is the offtake pipe. In order to secure the desired control of the blast therefore, the producer is provided with a central 60 offtake pipe 50, and as a result of this construction the blast, as it passes through the fuel bed will tend to maintain the active zone of the fuel bed of substantially barrel shape as shown in Fig. 2. Of course the lateral 65 spread of the active zone of fuel will be direct-

ly dependent upon the quantity of blast passing therethrough; that is, upon the load. But at all times the blast, regardless of its lateral spread, will be in contact only with chemically active material or fuel, and great 70 flexibility, or responsiveness to varying load, is thus secured.

Obviously if the blast did not tend to spread laterally through the fuel bed after passing out of the opening 40 the entire 75 active zone of the fuel bed would be supported upon the grate 43, but as stated, in actual practice the blast does tend to spread laterally. While the grate 43 directly supports the major portion of the active zone 80 of the fuel bed, therefore, nevertheless, the active zone of the fuel bed does, in operation, extend laterally a considerable distance so as to considerably overhang the grate 43. One reason for providing the layer of heat 85 insulating material 42 is to prevent heat transfer from the overhanging portion of the active zone of the fuel bed directly into the base member. It is also found, where the layer of heat insulating material 42 is 90 dispensed with and the fuel bed rests directly upon the metallic surface of the base member 22, or upon such a ring of heat insulating material as is shown in the producer described in my copending application 515,861, 95 that there is a tendency for wall action to develop. That is to say, because of the fuel resting upon a solid or rigid and comparatively smooth surface the resistance to the travel of the blast along that surface is somewhat less than the resistance to the travel of the blast through the fuel bed itself. Therefore there is a tendency, with such a construction, for the blast to travel laterally an 100 excessive distance, and it has even happened that this spread due to wall action has been such as to extend the active zone of the fuel bed into contact with the shell 21. This condition, which would not normally be present but which might sometimes occur with the 105 producer operating under extremely heavy load, is particularly undesirable and the layer of finely divided heat insulating material 42 effectively prevents it. Where a layer of 110 finely divided material of the character specified is used a path of less resistance to the travel of the blast does not exist, for the fuel imbeds itself in the material of the layer 42 and the resistance to flow of the blast is, if anything, greater than through the fuel bed 115 itself.

When operation of the producer is started, a layer of material 42 should be placed in the trough of the base member, but during 120 operation of the producer this layer is automatically renewed, for the fine fuel tends to work down and collect upon the base member, and to assume a definite angle of repose; and there is, thus, little or no tendency 125 for the finely divided fuel adjacent the base 130

member to pass through the opening 40, or to be consumed during the gas making reactions.

If the blast were so controlled as to prevent lateral spread and to thus so localize the active zone of the fuel bed that it would not spread laterally beyond the periphery of the grate the problem of ash removal would be comparatively simple. But in actual practice it does thus overhang the grate and the grate is, therefore, provided with a scraper member 47, which as shown most clearly in Fig. 11, is curved, the arrangement being such that as the grate is rotated, in the direction of the arrow in Fig. 11, any ash surrounding the upstanding flange 41 will be moved toward the center of the producer and will fall through the opening 40 into the ash pit. Where the conventional fire brick lining is dispensed with, and the layer 42 consists of finely divided fuel, the tendency to form clinker during gas generation is considerably decreased, but nevertheless in the operation some clinker may be formed. Any such clinker will gradually work down through the active zone of the fuel bed as the fuel is consumed, into the path of the scraper 47 and will, along with ashes, be moved toward the center of the producer, on to the spiral grate which will feed it downwardly through the opening 40 into the ash pit. As is most clearly shown in Fig. 2, the outer end of the scraper 47 is upturned at an angle which substantially corresponds with the boundary of the active zone of the fuel bed. As shown this angle is substantially 45° , but of course with different fuels and with different sizes of producers this angle might be different, and no definite angle of inclination for the upturned portion of the scraper may be fixed upon, therefore, but it should be given such inclination as corresponds with the particular type of producer with which it is used. In order to remove all the ash which is formed the scraper must extend laterally the distance of the greatest lateral extent of the active zone of the fuel bed. The active zone of the fuel bed, however, as set out above, is somewhat barrel shaped so that its greatest lateral extent is substantially midway the grate and the gas offtake 50. If the scraper is made flat, therefore, it will during operation tend to move toward the center of the producer finely divided fuel which is accumulated near the base but which has not been at any time a part of the active zone of the fuel bed and will thus decrease the resistance to flow of the blast with resulting lateral spread of the blast through this part of the fuel bed. By upturning the end of the scraper at an angle corresponding with the outer boundary of the active zone of the fuel bed this condition is avoided and only ash is removed.

As stated above a blast of air and moisture

is introduced through the opening 40 into the fuel bed to cause the generation of gas, the resulting gas passing off through the central draft tube 50 and the pipe 51, lying within the generator shell, to the offtake passage 52, which is located within the base member 22, this offtake passage having connected thereto the offtake pipe 53.

The producer may be either suction or pressure operated. Where it is pressure operated the blast will be forced through the opening 40 into the fuel bed under pressure. But the producer is preferably suction operated, the gas engine forming a part of the power plant being connected to the generating chamber of the producer which furnishes gas for operating the engine, the engine in turn furnishing the suction for operating the producer. In the construction shown the base member is provided with a second passage, or chamber, 60, which is positioned above the offtake passage 52, the two passages being separated by means of a partition 61, the construction being such that as the hot gas passes off from the generating chamber through the pipe 51, and offtake passage 52 it will flow over the partition 61 and heat that partition. As shown, particularly in Fig. 4 the partition 61 is somewhat inclined toward one side, and is provided with a pocket or depression 62 at one extreme side, into which opens the water supply pipe 63 the other end of which opens into the vessel 64 of the water feed. This vessel is of a generally conical shape, and is adapted to receive and support a bottle or other container 65 which is first filled with water and then placed in inverted position with its open end within the vessel 64 and at a height corresponding to the desired level of the water within the vaporizer chamber or passage 60. As shown the pipe 63 is provided with an elbow 66, the two sections of the pipe being arranged at substantially right angles to each other and the construction being such that the two sections of pipe may be moved relative to each other to raise or lower the vessel 64, and the bottle 65 associated therewith, to correspondingly raise or lower the level of the water within the vaporizer 60. In order to effect this variation in the water level within the vaporizer the base member is provided with a lug 67, having a passage therein within which is positioned a bolt 68 having a hook or loop at the lower end surrounding the pipe 63, the upper end being threaded and having suitable adjusting nuts 69, the construction being such that by proper manipulation of the adjusting nuts 69 the pipe 63 may be raised or lowered to cause corresponding raising or lowering in the water level within the vaporizer 60.

Ordinarily, to secure the most desirable gas making conditions the proportion of moisture to air within the blast should be

maintained substantially constant. The construction described just above is adapted to accomplish this desired control. As the heated gases pass off through the offtake passage 52 they heat the partition 61, which in turn heats the water within the vaporizer causing it to give off vapor which is taken up by the incoming air which enters through the opening 70, passes over the surface of the water within the vaporizer 60, taking up moisture as it does so, and then passes into the ash pit through the opening 71, whence it passes upwardly into the fuel bed. Obviously more gas will pass through the passage 52 under heavy load than under light load, and therefore more heat will be transferred into the water within the vaporizer under heavy load than under light load. But at the same time more air is required under heavy load than under light load, and the proportions of air and moisture thus tend to remain the same under varying loads. But in addition, the level of the water within the vaporizer is partly dependent upon the load upon the producer, for at heavy load there is greater suction upon the vaporizer and therefore greater tendency towards the formation of vacuum than is the case under lower load; and therefore with increasing or decreasing load the level of the water within the vaporizer will rise or fall to cover a greater or less portion of the inclined partition 61 and to at the same time expose a greater or less surface to the air passing through the vaporizer. If, for example, the load should suddenly be increased, therefore, the suction through the vaporizer would correspondingly increase and the level of the water therein would rise. This extra water would spread out over a part of the partition 61 which had not been theretofore in contact with water and the important result would be the rapid generation of moisture, to give at once the necessary excess of moisture needed for the immediate excess of air drawn in. Then as a greater quantity of heated gas passes through the offtake passage 52 the temperature of the entire quantity of water within the vaporizer will be raised sufficiently to generate the necessary quantity of moisture and thus give the desired proportion of moisture to air.

Preferably a plurality of baffles or partitions 72 are provided which are so arranged that as the air passes through the vaporizer it is maintained in contact with the water for a greater length of time and ample opportunity for absorbing of moisture afforded. As shown, particularly in Fig. 4, the vaporizer is provided with a second port 73 corresponding to the port 70, the base member being provided with a plate 74, having an opening 75 therein which registers with the port 70 to admit air, the remainder of the plate serving to close the port 73 except

when the plate 74 is removed. This opening 73 permits access to the vaporizer so that it may be cleaned out. The offtake passage 52 is also provided with a clean-out port closed by the plug 76.

The ash pit is provided with a door 80, which is pivotally connected to the hinge member 81, which member is in turn pivotally connected to the base member 22, the construction, as shown, being such that if the handle portion 82 of the hinge member 81 is raised part way and released the door may be caused to assume a substantially horizontal position, with the upper edge of the door contacting with its seat to hold it open, to permit free access to the ash pit. The door having been placed in this open position may be closed by lifting up on the handle 82 to swing the door entirely clear of its seat and then dropping the handle when the door will assume a vertical position to close the ash pit. The construction results from pivoting the door as shown with the axis pivot above the center line of the door and offset from the general plane of the door.

The rotatable shaft 44, upon which the grate is carried, is provided with an operating handle which as shown preferably consists of an elbow portion 85 having four radially arranged handles 86, spaced equal distances apart, by means of which a suitable rotation of the grate may be secured.

As set out above the producer is directly connected to a gas engine, the producer furnishing gas for operating the engine, the engine in turn during its operation furnishing the suction for operating the producer. The offtake pipe 53, therefore, is connected to the inlet pipe of the gas engine, but because of the presence of impurities, such as tar and the like, in the gas, which would tend to foul the working members of the engine and interfere with its efficient operation, purifying apparatus of some sort, within which the gas may be treated to remove impurities therefrom, is generally necessary in power plants of this character. As shown, generally, in Fig. 1, the offtake pipe opens into a purifier or separator which is designated generally by the numeral 100.

This purifier consists of a cylindrical shell or drum 101, the open upper end of which is, during operation, closed by means of a cover or top 102. The shell 101, and the top 102 are preferably made of thin sheet metal, which may be of substantially the same gauge as that used in making the shell 21 of the producer or of somewhat lighter gauge, and the upper free edge of the drum 101 is rolled or beaded as shown at 103, to provide a seat for the top, suitable packing 104 being interposed between the top and the seat 103, to prevent leakage. The top is preferably provided with a plurality of depending guides 106 which extend down into the shell 101 to

properly center the top when it is in position. Intermediate its ends, and preferably substantially midway of its height, the shell 101 is provided with a transverse partition 105, which divides it into two chambers and upper 107 being adapted to house the purifying mechanism while the lower 108 acts as an equalizer to prevent undue pulsations in the gas passing through the purifying chamber 107, as a result of the operation of the gas engine.

The partition 105 is provided with a substantially central opening therein, and a hollow fitting 110, which is secured to the partition 105 in any desired manner, surrounds this opening, the upper end of this fitting being cone shaped to receive a correspondingly conical shaped opening in the member 111 which serves to support the purifying material through which the gas, entering the chamber 107 from the producer passes on its way to the engine. This member 111 preferably consists of a pan shaped member, having upstanding side walls 112, and a somewhat oval false bottom 113. The false bottom 113, as shown particularly in Figs. 2 and 12 is provided on its upper face with a plurality of concentric grooves 114, and is also provided with a plurality of radially arranged slots or passages 115. This false bottom has positioned upon its upper surface a layer of fabric 117, which is preferably a good grade of flannel, or the like, such as the wool filter cloth which is an article of commercial use. This cloth is covered with a layer of finely divided purifying material 118, which material is preferably of the same character as the fuel used in the producer. If the producer is operating upon charcoal the layer of purifying material 118 will consist of finely divided charcoal or charcoal dust. If the producer is operating upon coke this layer will consist of coke dust or breeze. The primary purpose of the cloth 117 is to provide a support for the finely divided purifying material which permits the ready passage of the gas therethrough, but prevents any of the finely divided purifying material being carried along with that gas. The filter cloth is preferably stretched smoothly and somewhat tightly over the false bottom 113, any desired means being used for retaining this cloth in position and properly stretched. Preferably, however, the cloth is retained in position by means of a piece of rope 120 which is pressed down into a suitable groove 121, within the member 111, the proportions of the groove being such that as the rope is pressed into position it will draw the cloth tight, and will remain in position holding the cloth properly stretched. If desired a spring, such as is disclosed in the above referred to applications may be utilized for this purpose but experience has shown that a piece of rope is

just as satisfactory and considerably cheaper and less difficult to assemble.

The gas introduced into the chamber 107, through the offtake pipe 53, passes downwardly through the layer of purifying material, the layer of cloth 117, and thence through the passages 115 in the false bottom, impurities being removed as it passes through the purifying material, the purified gas passing through the member 110 into the chamber 108 and thence outwardly through the pipe 123, which is connected to the inlet pipe 124 of the gas engine.

As the engine 122 operates pulsations will be set up in the pipe 123 which have a tendency to agitate the purifying material 118 and interfere with its effectiveness of operation and in order to prevent this a chamber 108 is provided which chamber acts somewhat in the nature of an equalizer to absorb these pulsations and prevent them from affecting the purifying material 118.

The function of the concentric grooves 114 is to prevent localization of the gas into streams as it passes through the layer of purifying material, as would be the case if the upper surface of the false bottom 113 were smooth and the passages 115 were as widely separated as shown. But by providing these concentric grooves the gas is free to pass through substantially the whole area of the layer of purifying material and after it passes therethrough can travel through the various grooves to the passages 115.

The false bottom 113, as shown, is preferably oval shaped, since such construction permits of maintaining the layer of fabric 117 snugly in contact with the false bottom 113 throughout its extent. If this layer of fabric does not lie snugly against the false bottom 113 it will tend to vibrate or oscillate during operation of the apparatus and thus disturb the layer of purifying material, the effect being so pronounced at times as to break the continuity of this layer of purifying material thus allowing some of the gas to pass through without being subjected to purifying action.

Because of the character of the layer of purifying material the presence of considerable quantities of water or other liquid impurities within the gas will tend to destroy its effectiveness. Water carried by the gas will be removed therefrom, along with other impurities, as the gas passes through the purifier and this water will tend to clog up the purifier. In order to prevent this a condenser is interposed within the delivery pipe 53, between the purifier and the producer. As shown this condenser preferably consists of several extra lengths of pipe 130, but of course any other desired type of condenser may be used.

Inasmuch as the impurities which are removed in the purifier are deposited on the

upper surface of the layer of material 118 the tendency during operation is for these impurities to form a layer or crust over the top surface of the purifying material to 5 clog up the passages therethrough and destroy the effectiveness of the purifier. In general practice the layer 118 is formed by placing a quantity of the purifying material to be used upon the false bottom 113, sufficient 10 of this material being used to form a layer whose upper surface is substantially level with the upper edge of the flange 112. Impurities deposited upon this layer of purifying material will tend to build up its thickness. If this layer of material is removed the 15 original purifying material will be found to have its original effectiveness. In order to permit removal of this layer of material a scraper, which consists of a curved blade 135, 20 to which is attached a rake member 136, is mounted upon the lower end of the rotatable shaft 137, which is positioned within an opening in the top 102, a suitable enlargement or handle 138 being provided, upon the outside 25 of the top, to permit ready manipulation of the scraper. The handle 138 is preferably substantially round with a depending flange 139 which contacts with the upper surface of the top and tends to prevent leakage through 30 the opening in which the shaft 137 is mounted. A suitable spring 140 is positioned between the inner face of the top 102 and a disc 141 carried by the shaft 137, to hold the flange 139 against the top, while at the same 35 time permitting ready rotation of the shaft 137 and the scraper member carried thereby. The blade 135, as shown particularly in Fig. 2 rests upon the upper surface of the flange 112 and as this blade is rotated it tends, because 40 of its curvature, to scrape off any excess material and force it over the edge of the flange. Sometimes the material deposited upon the layer 118 tends to cake but the rake member 136, which consists of a wooden bar having 45 a plurality of teeth 143 imbedded therein, will break up this coating, as the shaft 137 is rotated, to thus restore the cleaning effectiveness of the apparatus.

Details of construction of the engine 122 50 are not shown since this engine may be of any desired type. The particular engine shown is an engine of the character shown herein, details of construction of which are shown in the patent to Charles F. Kettering and William A. Chryst, No. 1,341,327 dated May 25, 1920. However, any other type of engine 55 which is adapted to operate upon producer gas may be used. As stated above during operation the purified gas passes from the chamber 108 into the pipe 123 which is connected to the inlet pipe 124, of the engine, and the exhaust gas resulting from the combustion 60 of this gas within the cylinder of the engine 65 passes outwardly through the exhaust pipe

145, into the vent pipe 146, which is connected to the atmosphere.

While the engine 122 during operation furnishes suction for blasting the fuel bed to cause the generation of gas within the producer, in a plant of this character a starting blower is ordinarily provided so that the producer may be blasted during the starting or blowing up period, to bring it up to good gas making conditions or until a gas is generated 70 which is of a proper quality for operation of the engine. As shown this blower, which is designated generally by the numeral 150 is of the conventional centrifugal type, operated by a suitable motor 151, the inlet 152, of the 75 blower, being connected to the offtake pipe by means of a branch pipe 153, the motor preferably being positioned between the producer and the purifier, thus lessening the load on the motor during its operation, although it 80 will function very satisfactorily if it is positioned beyond the purifier. The outlet pipe of the blower, 154 is connected to the vent pipe 146, the gas generated during the operation 85 of the blower being vented to the atmosphere through this pipe. The housing for the blower has attached thereto a three-way valve fitting 155, one port 156 of this fitting being connected to the pipe 153, another port 157 being connected to the pipe 158 which opens 90 into the chamber 107 of the purifier, the third port being the inlet port 152 of the pump housing. Positioned within this fitting is a rotatable valve 160, which, as shown particularly in Fig. 6 is provided with a passage or 95 groove 161, the construction of the valve being such that when in one position the pipe 153 is connected to the pipe 158, while the inlet port 152 of the pump housing is entirely disconnected from either the pipe 153 or the pipe 158 which position is shown in Fig. 6; while in another position the pipe 153 and the inlet port 152 are connected and the pipe 158 is entirely disconnected from either. In 100 starting, and during such time as the blower 105 is operating the valve 160 is positioned to connect the pipe 153 and the inlet port 152, in which position the gas drawn off through the offtake pipe may be vented to the atmosphere 110 through the pipe 154 and the vent pipe 146. As soon as the gas becomes of suitable quality, 115 which may be determined by igniting the small jet of gas that escapes through the pipe 165, which pipe opens into the offtake 154 of the pump, the blower is stopped and the valve 160 positioned to connect the pipe 130 to the pipe 158. The engine 122 is then started 120 and the suction of the engine causes blasting of the fuel bed and draws the generated gas through the purifying system to the combustion chamber of the engine. The engine is 125 preferably provided with an electrical starting system, but this of course is not essential since the engine can be started by hand.

The valve 160 is preferably provided with 130

suitable means for holding the blank part 166 thereof tightly against its seat to prevent leakage therethrough. Obviously when the pipe 153 is connected either to the inlet 152 of the pump or to the pipe 158 it is a matter of indifference if there is some slight leakage around the valve from the pipe 153 into which ever of these two ports the pipe is connected to; but it is undesirable to have leakage around the valve into or from that one of these ports which is not connected to the pipe 153. Therefore means is provided for holding this blank portion of the valve tightly against its seat to prevent this undesirable leakage. This means preferably consists of two spring pressed members 167, which, with their cooperating springs 168, are positioned within suitable sockets in the valve plug, the members 167 contacting with the valve casing to force the blank portion 166 of the valve tightly against its seat.

The valve 160 preferably has associated therewith a switch for controlling the motor 151, the construction being such that the motor is automatically started to operate the blower when the valve 160 is positioned to connect the pipe 153 with the inlet port 152 of the pump and is automatically stopped when the valve is moved into position to connect the pipe 153 to the pipe 158. This switch consists of a plate 170, of insulating material, suitably connected to the valve fitting, which plate carries two contacting members 171 and 172, one of which is connected, through a suitable conductor, to one terminal of a battery, or other suitable source of electrical potential, the other being connected, through the conductor 173 to one terminal of the motor 151 the other terminal of the motor being connected through the conductor 174 to the other terminal of the battery, or other source of electrical potential. The handle 175, for operating the valve 160 has attached thereto a strip 176 of conducting material which is suitably insulated from the said handle, the construction of this strip, and the relative positioning of the handle with respect to the valve, being such that when the valve is turned to connect the pipe 153 to the port 152 the strip 176 will be so positioned as to contact with each of the contact members 171 and 172 to thus close the motor circuit and start the blower; but when the valve is turned to disconnect the pipe 153 from the inlet port 152 and connect that pipe to the pipe 158 this strip 176 will be so positioned as to not connect the two contact members 171 and 172, the motor circuit thus being broken. In Fig. 2 the valve handle 175 is shown positioned with the strip 176 out of contact with the contact members 171 and 172, and with the motor circuit thus open. This is the position which corresponds with the positioning of the valve shown in Fig. 6. The engine 122 may be provided with any

suitable form of mixture regulating device. The engine is normally provided with a simple mixing valve which is adapted to mix the fuel and air in proper proportions. It may of course be provided with a conventional form of carburetor. This mixing valve is indicated diagrammatically at 180. It has been found in operation that an engine of the character shown herein, which is designed for operation upon a liquid fuel such as kerosene or gasoline, when operating upon producer gas will give improved operating results if the inlet pipe is provided with a port permitting the introduction of some air into the gaseous fuel before it passes into the mixing valve for admixture with more air to give the proper proportions for the desired combustible mixture. In other words instead of depending entirely upon the mixing valve to give the desired combustible mixture the inlet pipe is provided with a fixed opening through which atmospheric air is drawn in under the suction of the engine and the mixing valve operates to admit a supply of air additional to this preliminary mixture of air and gas the quantity of air being easily controlled to give any desired combustible mixture. As shown this opening in the inlet pipe through which preliminary air is admitted is provided with a short section of pipe 181, but this section of pipe may be dispensed with if desired.

In Figs. 7 and 8 is shown a slightly modified form of producer. This producer comprises a metallic shell 200, which is substantially identical in construction with the shell heretofore described. But the base member, in this modification, is of somewhat different construction from the base member 22. This base member preferably consists of an upper section 201 and a lower section 202. The upper section comprises an inclined wall 203, which is inclined downwardly to give a cavity therein which is substantially frusto-conical in form the lower end of the cavity being closed by means of a suitable grate, which as shown, consists of two slotted members 204, each of which is pivoted at its opposite ends to depending lugs 205, carried by the inclined wall 203. Each of the members 204 is provided with a depending arm 206, each arm being pivotally connected to the bar 207, the free end of this bar being in turn pivotally connected to an operating lever 208 mounted upon the rock shaft 209 which may be operated, in any suitable fashion, from outside the producer.

The lower part 202 of the base incloses an ash pit 210, provided with a suitable door 211, which is pivotally mounted so that it may be readily opened, the construction being such that whenever released the door will fall into closed position.

The upper section 201 of the base is provided with a flange or partition 215 which

extends outwardly from, and is carried by the wall 203, which partition at its outer edge is in turn provided with a flange 216, arranged at substantially right angles to the partition and extending on both sides thereof. The lower portion of the flange 216 is so constructed that when the two sections of the base member are in desired position the free edge of this depending portion of this flange will contact with a cooperating upstanding flange 220 on the lower member 202, to form a tight joint therewith. The upper member 201 of the base is also provided with a depending flange 221, substantially concentric with the flange 216, which flange is also so constructed that when the base member is in assembled position it will contact with the cooperating upstanding flange or rib 222, on the lower base member. It is obvious from this construction that, when the two sections of the base member are in assembled position the upper wall 219 of the base member 202, the partition 215, the depending portion of the flange 216, the depending flange 221 and the respectively cooperating ribs or flanges 220 and 222 carried by the member 202 of the base will form a closed circular passage 223. The base member 201 has a vertically arranged passage 225 therein, the lower end of which opens into the passage 223 and the upper end of which receives the pipe 226, which extends upwardly into the shell 200 of the producer, and carries upon its upper end the central draft tube 227, through which the generated gas passes off from the generating chamber of the producer. The member 202 of the base is provided with a passage 228 one end of which opens into the passage 223 and the other end of which receives the delivery pipe 53'. By means of this construction the generated gas passes through the draft tube 227, the passage 223 and the delivery pipe 53', to any desired place of use or storage.

The upper section 201 of the base is also provided with a depending flange 230, which is concentric with and substantially the same diameter as the flange 216, a suitable ring 50 or band 231 being so positioned that it cooperates with the depending flange 230 and the upstanding portion of the flange 216 to inclose a passage or chamber 232 which is coaxial with the passage 223 and is separated 55 therefrom by means of the partition 215. Of course the ring 231 could be dispensed with if desired and the depending flange 230 and the upstanding portion of the flange 216 cast integral. The construction shown 60 is desirable, however, because of its greater ease of manufacture. An opening 235 is provided in the ring 231 connecting the interior of the passage 232 to the atmosphere, and the member 236 which is attached to the base member 201, extends into the cavity within

the member 201 and connects the passage 232 with the cavity inside the base. And inasmuch as the base member, when the device is assembled, supports the shell 200 and also supports the fuel bed within that shell, any air passing into the passage 232 through the opening 235 will also pass through the pipe 236 into the interior of the generating chamber of the producer. 70

In order to introduce a suitable quantity of moisture along with the air a layer of water is maintained within the passage 232, the hot generated gases passing through the passage 223 heating up the partition 215 and the cooperating metallic members of the base, 80 these in turn heating the water within the passage 232 to cause the generation of vapor which is taken up by the ingoing air of the blast as it passes through this passage to the generating chamber of the producer. A proper water supply is maintained by means of the same general type of fuel feed as is described above. For purposes of easy description this type of fuel feed is designated as a "chicken feed" type, and consists essentially of a pipe 237, one end of which opens into the passage 232 and the other end into a funnel shaped member 238 which is adapted to receive and support the bottle or container 239, which is shown as preferably constructed of metal, though it may be a glass bottle, or any other suitable type of container. The level of the water in the member 238 and in the passage 232 is dependent upon the positioning of the outlet of the container 239. As the water level falls below that air will move up into the container and water flows therefrom to bring the level in the passage 232, which is for purposes of easy description designated as a vaporizer or saturator, up to the desired level. 95

During operation a layer of ashes is at all times maintained on the grates, and within the cavity in the producer base member, which serves to heat insulate the active zone 116 of the fuel bed from the base member, and thus cuts down the heat losses which would otherwise result from transfer of heat from the active fuel into the base member and radiation therefrom into the atmosphere. 115 Of course, in practice the thickness of this layer of insulating ash will vary, being thinnest immediately after the grates have been manipulated to shake down the ash. Ordinarily conditions will be such that the layer 120 of ash will extend approximately up to the level of the blast inlet pipe 236, the blast thus being introduced into the lower level of the active fuel bed. But as the ash may not be shaken down over a period of several hours its general level may vary materially. 125

The producer is preferably supported upon suitable legs 241 which as shown have threaded sockets in the upper ends thereof adapted to receive extensions or bolts 242 which are 130

connected to one end of the shell 200. These extensions pass through suitable openings in cooperating lugs carried by the two members of the base, the construction being such that as the legs are screwed on to the lower ends 5 of the extensions 242 the members of the producer will be drawn tightly together. Packing 243, which may be of any suitable character, is positioned between the shell 10 and the base member to prevent leakage.

In Figs. 9 and 10 is shown still another modification of the producer, which is also provided with a shell 300 substantially identical in construction with the shell 21 described above. The base member is also quite similar to the base member described above in connection with the modification shown in Figs. 1 and 2, this base member being provided with substantially 15 the same means for holding it in assembled position with the shell, and with the same type of leg construction as already described. This base member is also provided with an upstanding flange 301, positioned about a 20 central opening 302, a concentric upstanding flange 303 being positioned intermediate this flange 301 and the peripheral flange 304 which serves to center the shell 300. The trough or depression between the two flanges 25 301 and 303 is adapted to contain a layer of finely divided heat insulating material of the character heretofore described. This trough is also provided with a series of curved partitions 310, which are shown most 30 clearly in Fig. 10, which partitions divide the circular trough between the flanges 301 and 303 into a plurality of pockets. The ash pit 311 is provided with an upstanding standard 312 within which is rotatably 35 mounted a shaft 313, which extends, coaxially, up through the opening 302 and carries a flat perforated grate 314 upon the upper end thereof. Ashes resulting from the combustion of that portion of the active zone 40 of the fuel bed which is directly supported upon the grate will pass downwardly through the perforations in the grate into the ash pit. But as described above the active zone 45 of the fuel bed spreads laterally and over- 50 hangs the grate, ashes and clinker thus working down around the grate. In order to remove this ash the grate is provided with two scrapers or vanes one of which, 315, is longer than the other, 316, each scraper being 55 curved, so that upon rotation of the grate in the direction indicated by the arrow in in Fig. 10 ashes will be moved toward the opening 302 and caused to pass downwardly 60 into the ash pit. By making one of these 65 scrapers longer than the other more desirable results are secured, for where both are made of the same length the ash tends to pack as it is crowded toward the central opening so as to cause jamming of the grate 70 and prevent ready rotation and removal of

the ashes. But by making one scraper longer than the other this condition is avoided, the shorter scraper tending to handle the ash in the inner zones and the longer scraper the ash in the outer zones.

While the producer of the character described, in which no lining is used, is comparatively free from formation of clinker there will be at times some clinker formation. If these clinkers are of substantial size they obviously cannot pass downwardly through the perforated grate when they are moved on to that grate through the operation of the scrapers. But, during operation, as the grate is rotated any clinkers which are formed will be moved by the scrapers into contact with the partitions 310 and crushed or ground into such small size that they will readily pass through the grate.

Means for providing saturation is quite similar to the means described above in connection with Figs. 1 and 2. The base, around the ash pit is provided with a partition 320 which divides that portion of the base into a lower passage 321, to which is connected the pipe 322 through which the hot gases pass downwardly into this passage, and thence outwardly to any desired place of use or storage through the offtake pipe 53". The upper of these two passages or chambers 325 serves 85 as a vaporizer or saturator, water being introduced thereto through a chicken feed mechanism, designated generally by the numeral 326 which is of the character heretofore described, air passing into this passage through the opening 327 in the side wall, and after passing over the surface of the water within the saturator to absorb moisture therefrom passes into the ash pit beneath the grate, 90 through the opening 328. The operation of 95 this saturator is substantially identical with that heretofore described.

This modified form of producer is shown as provided with a fuel feed, which may be of any conventional and suitable construction; but which is preferably of the character described in the above referred to copending application of Harry F. Smith No. 515,861, filed November 17, 1921, now Patent 1,772,642, dated August 12, 1930. By using 110 such a fuel feeder continuous operation of the producer may be secured. The other forms of producers as shown in Figs. 1 and 2, and in Figs. 7 and 8, are provided with a cover for the fuel supply opening instead of a fuel 115 feeder, but each form is adapted to receive a fuel feeder, if desired, so that continuous operation, without the necessity of any shut down for the introduction of new fuel, may be obtained.

Because of the construction described above, in which the ordinary lining for the producer is dispensed with, the blast being so controlled that the active zone of the fuel bed is at all times during operation surround- 120 125 130

ed by a zone of inactive fuel which serves to heat insulate the active zone of the fuel bed from the metallic shell of the producer, and also because of the base construction in which the active zone of the fuel bed is at all times heat insulated from the base of the producer by means of a layer of suitable heat insulating material, and because of the grate construction in which that portion of the grate 10 which is in direct contact with the active zone of the fuel bed is supported upon a single small shaft, so that the portion of the grate which is in direct contact with the active portion of the fuel bed is entirely out of direct 15 thermal contact with the base of the producer, and the sole path of heat conductance from the grate is through the single supporting shaft, loss of heat from the active zone of the fuel bed by radiation from the shell and 20 base of the producer into the surrounding atmosphere is substantially prevented. Furthermore since the blast is free to choose the path of least resistance and as it passes through the fuel bed is at all times in contact 25 with chemically active material, the starting period is greatly decreased. Also because of this construction heat losses during operation are minimized and therefore a gas of high heat value is obtained, for generally, the 30 greater the heat losses the greater the percentage of non-combustible within the gas.

Furthermore this construction lends itself to the elimination of wall action along the lining, and this in turn results in a concentration 35 of the blast. And of course concentration of the blast means better gas making conditions, and quicker starting. Again the producer is so constructed that the saturator or vaporizer receives heat by direct conduction 40 from the active zone of the fuel bed, through the layer of insulating material, and concomitantly receives heat from the hot off-going gases passing through the passage 52. As a result the heat input into the water within 45 the saturator is maintained substantially constant during operation. For if the layer of ash around the grate and the base builds up during operation, thus cutting down transfer of heat by conduction into the saturator, at 50 the same time the thickness of the layer of active fuel between the base and the central draft tube 50 is decreased so that the offgoing gas leaves the producer at a slightly higher 55 temperature. And on the contrary if the ashes have just been removed and the active fuel is thus separated from the saturator by a thinner layer of insulating material, with a consequently greater transfer of heat by conduction into the saturator, at the same 60 time the thickness of the layer of fuel between the grate and the gas offtake is correspondingly increased so that the offgoing gases will be at a lower temperature. As a 65 result uniform saturation is obtained.

66 This construction also is instrumental in

securing suitable saturation at starting, without unnecessary delay in the introduction of moisture into the blast. For when the producer is started the layer of insulating material between the active zone of the fuel bed and the saturator is at a minimum, being merely the permanent layer of heat insulating material. And consequently the resistance to the transfer of heat through this layer of heat insulating material is at a minimum. This feature is particularly desirable where the fuel has not any considerable quantity of volatile hydrocarbons in it. Where there are considerable quantities of volatile hydrocarbons these are normally driven off during the 70 earlier action of the producer giving a gas of higher B. t. u. and it is desirable where such fuel is being used to delay the introduction of moisture until the volatile hydrocarbons have been substantially driven off, the 75 enrichment of the gas resulting from the introduction of moisture serving to compensate for the falling off in B. t. u. that would normally result because of the volatile hydrocarbons being no longer present therein, thus 80 giving a substantially uniform B. t. u. throughout operation of the producer. But where fuel is used which has not considerable quantities of volatile hydrocarbons therein and the introduction of moisture is considerably delayed, the gas at first obtained 85 will be of less B. t. u. than the gas subsequently obtained when moisture is introduced. When such fuel is used therefore it is desirable 90 to introduce the moisture from the beginning of operations and the construction described above lends itself to this condition for if the producer is started with only the minimum, and permanent, layer of heat insulating material on the base the transfer 95 of heat into the saturator takes place quickly and thus gives the desired saturation. Of course if a fuel is used which contains substantial quantities of volatile hydrocarbon 100 the layer of heat insulating material on the base may be increased as needed to give any desired delay in the introduction of moisture.

105 As stated above the starting blower is preferably so positioned within the gas offtake pipe that during operation only the resistance to draft of the fuel within the generating chamber of the producer must be overcome. This positioning of the starting blower is not essential, since entirely satisfactory operation 110 may be secured by positioning the blower beyond the purifier; but it is desirable that the blower be so positioned as to subject it to small resistance, so that the quantity, or 115 volume, of air, or blast, passed through the fuel bed during the starting operation will be the maximum for a given apparatus. For it has been found that the greater the quantity of air which is caused to contact with a given quantity of incandescent carbon, during 120 a given interval of time, the greater will 125

be the temperature of the incandescent carbon, and the better the quality of the gas. Positioning the starting blower as described, therefore, makes for the minimum starting, 5 or blowing up, period.

Furthermore, as stated above, it is desirable to so construct the apparatus that concentration of the blast will be secured during gas making operations. In the apparatus described, 10 and particularly in the form of apparatus illustrated in Figs. 1 through 4, this desired condition is secured partly by that construction which prevents spreading of the blast along the base of the producer. It 15 is still further secured, particularly in the form of apparatus disclosed in Figs. 1 through 4, by constructing the grate in such fashion that it does not tend to diffuse or spread the blast. It is obvious, from inspection 20 of the type of grate construction disclosed in Figs. 2, 3 and 4, that there is no tendency to cause a spreading of the blast after it leaves the upper end of the tuyère opening 40. As a result of this construction 25 the blast is concentrated so that a large quantity of air will be brought into contact with the incandescent carbon, this in turn causing the carbon of the fuel bed to be maintained at a higher temperature than is the case where 30 the same quantity or volume of blast is somewhat dissipated so that it is brought into contact with a larger quantity of incandescent carbon. Not only does this condition make for quicker starting, but it also results 35 in the securing of gas of a better quality, for it has been found that by increasing the concentration of the blast so that a large quantity of air is brought into contact with a given quantity of incandescent carbon, the 40 result is, for a given fuel bed depth and condition, a gas containing a greater percentage of combustible.

The gas generating system shown herein, 45 as illustrating a preferred embodiment of the invention, comprises an internal combustion engine which, as stated above, operates upon the generated gas and during such operation supplies the suction for blasting the fuel bed within the producer, to cause the generation 50 of the gas. Obviously in such a type of plant the gas engine, during operation, utilizes all of the gas which is generated; since the blast through the fuel bed which causes the generation of gas is caused entirely by the suction of 55 the engine during operation. The gas generating apparatus described herein is not, however, limited to a gas power plant of this character; but may be utilized for supplying 60 gas for any desired purpose. For example, a gas producer constructed in accordance with this invention, and, say, of the character disclosed herein, might be utilized for supplying gas for domestic purposes, such as cooking, heating, lighting, and the like. In such case 65 some type of pump or exhauster for drawing

a blast through the fuel bed to generate the gas, and for forcing the generated gas under suitable pressure to any desired place of use or storage would be connected to the offtake, or delivery pipe. But the producer would 70 function exactly as it does in the gas power plant disclosed in the drawing. And, of course, a part of the gas generated could be used for operation of an internal combustion engine, if desired, that gas being fed to the 75 inlet of the engine under slight pressure, instead of under suction as is the case where the engine functions as the pump or exhauster.

While the method herein described, and the forms of apparatus for carrying this 80 method into effect, constitute preferred embodiments of the invention, it is to be understood that the invention is not limited to this precise method and forms of apparatus, and that changes may be made in either without departing from the scope of the invention 85 which is defined in the appended claims.

What is claimed is:

1. A gas producer comprising a gas generating chamber, adapted to contain a fuel bed; a base member for supporting said fuel bed, a saturator in said base member, a gas offtake passage within said base member below the said saturator; a central draft tube within the generating chamber above said base member, a gas offtake pipe connecting the said draft tube to the offtake passage within the said base member; the saturator being so located within the base member as to receive heat on its upper side from the fuel bed resting on the said base member, and to receive heat on its lower side from the offgoing generated gases passing through the said offtake passage, whereby any increase or decrease in the thickness of the layer of ash on the base member to decrease or increase the quantity of heat transferred to the saturator from the fuel bed, will be accompanied by a corresponding increase or decrease in the temperature of the offgoing gases to increase or decrease the quantity of heat input into the saturator from such gases, said base member having a blast inlet opening therethrough, and a grate member positioned mainly within said blast inlet opening. 100

2. A gas producer comprising a gas generating chamber adapted to contain a fuel bed; a base member closing the lower end of said generating chamber and adapted to support the fuel bed therein; means for introducing a blast of air and moisture into the fuel bed within said generating chamber to cause the generation of combustible gas; and a layer of heat insulation permanently maintained upon said base during operation, consisting of finely divided unburned carbonaceous material of the character serving to constitute the fuel bed for the generation of gas but more finely divided than the bulk of the material of the fuel bed, said layer of heat in- 110 115 120 125 130

sulating material serving to cut down the transfer of heat from the active zone of the fuel bed into the base member.

3. A gas producer having a gas generating chamber adapted to contain a fuel bed having a laterally restricted active zone therein; and means for supporting said fuel bed, comprising a generally flat base member having a restricted central opening therein, 10 a worm grate positioned in said opening, means for rotating said grate to cause ash to move downwardly through said grate and the opening in which it is positioned, and a scraper carried by said grate and extending laterally over the base member, whereby upon rotation of the grate the scraper will move ash across the base member toward the said opening and the grate positioned therein, the grate in turn moving said ash downwardly 20 through the said opening, said scraper having its free end upturned to conform to the outline of the active zone of the fuel bed.

4. A gas producer comprising a gas generating chamber adapted to contain a fuel bed; a base member, having an opening therein, closing the lower end of said generating chamber, an upstanding flange surrounding said opening, a second upstanding flange, carried by said base member, surrounding the 25 first named flange and spaced therefrom, to form a trough adapted to receive finely divided heat insulating material; a grate positioned within said opening, a scraper arm carried by said grate and extending laterally 30 therefrom to overhang said trough, means for rotating the grate and the scraper arm carried thereby, and partitions in said trough cooperating with the said scraper arm during rotation of the grate to crush clinker and 35 the like.

5. In a gas producer comprising a gas generating chamber adapted to contain a fuel bed and means for introducing a blast of air and moisture into said fuel bed to cause the generation of gas; a saturator, having an opening therein connecting the interior of said saturator to the blasting means, the bottom of said saturator being inclined; chicken feed mechanism of the character described for 45 supplying water to said saturator; and a gas offtake pipe connected to the interior of said generating chamber and in heat exchange relation with the said saturator, whereby the heated generated gases passing off through 50 the offtake pipe will heat the said saturator and the water contained therein.

6. In a gas producer comprising a gas generating chamber adapted to contain a fuel bed and means for introducing a blast of air and moisture into said fuel bed to cause the generation of gas; a saturator, having an opening therein connecting the interior of said saturator to the atmosphere and another opening connecting the interior of said saturator to the blasting means, the bottom of said 65

saturator being inclined; chicken feed mechanism of the character described for supplying water to said saturator; and a gas offtake pipe connected to the interior of said generating chamber and in heat exchange 70 relation with the said saturator, whereby the heated generated gases passing off through the offtake pipe will heat the said saturator and the water contained therein, the said chicken feed mechanism having adjusting means coacting therewith for varying the relative positioning of the said chicken feed mechanism to control the normal level of the water within the said saturator. 75

7. A gas producer comprising a gas generating chamber adapted to contain a fuel bed; a base member closing the lower end of said generating chamber and adapted to support the fuel bed therein; means for blasting the fuel bed within said generating chamber to cause the generation of combustible gas; an offtake passage within said base member, a gas offtake pipe connecting the interior of the generating chamber to said offtake passage; a saturator within said base member in heat exchange relation with said gas offtake passage, whereby the lower wall of said saturator will receive heat from the heated generated gases passing off from the generating chamber through the said offtake 80 passage; said saturator having an opening therein connecting the interior of said saturator to the blasting means, the bottom of said saturator being inclined; and liquid level controlling mechanism for controlling the supply 85 of water to said saturator to a level normally exposing a portion of the inclined bottom of said saturator, said mechanism being responsive to the differences in pressure within said saturator due to variations in load on 90 the producer to thereby increase the water level therein as the pressure decreases within said saturator and vice versa. 95

8. A gas producer comprising a gas generating chamber adapted to contain a fuel bed; a gas offtake passage connected with said generating chamber, through which the generated gases pass off from the generating chamber; a saturator coacting with said offtake passage in such wise as to be in heat receiving relation to the offgoing gases, said saturator having an opening therein connecting the interior of the said saturator to the generating chamber of the producer; and means for supplying water to the interior of 110 said saturator, said means being adapted to automatically vary the quantity of water within said saturator to accord with variations in the quantity of generated gases passing in heat transferring relation to the water 115 in said saturator. 120

9. A gas producer of the character described, comprising a gas generating chamber adapted to contain a fuel bed having a laterally-restricted active zone therein; a base 125

member having a central blast opening therein, said opening being of less diameter than the said base, and a worm grate positioned within said blast opening, the base member and grate being adapted to support the fuel bed within the generating chamber, the worm grate and blast opening being adapted for passage of the blast thru the said blast opening and grate without causing substantial lateral spread thereof.

10. A gas producer comprising a gas generating chamber adapted to contain a fuel bed having a laterally-restricted active zone therein; and means for supporting the said fuel bed comprising a generally flat base member having a centrally-arranged blast opening therein, a worm grate mounted within said opening and carrying a member extending over the said flat base member, and means for rotating said gate to cause ash within the generating chamber and above the base member to move from the said base member thru said blast opening.

11. A gas producer comprising a gas generating chamber adapted to contain a fuel bed of solid carbonaceous material; a base member for supporting said fuel bed having a blast inlet opening therein of substantially less diameter than the said generating chamber; a draft tube positioned within said generating chamber and adapted to be surrounded by fuel during operation, the draft tube and blast opening being so proportioned and positioned close to each other that the path of travel of the blast through the fuel bed within said generating chamber during operation will be laterally restricted to limit the maximum extent of the active zone of said fuel bed so that such active zone will be during operation surrounded by a zone of inactive fuel, and a layer of solid finely divided heat insulation material considerably smaller in size than the bulk of the material of the fuel bed permanently maintained during operation upon said base member about said blast inlet opening and between said base member and the active zone of the fuel bed for heat insulating the active zone of the fuel bed from the said base member to confine the heat within said active zone, the pieces of fuel of the fuel bed directly resting thereon becoming imbedded in the finely divided heat insulating material and serving to further insure the said lateral restriction of the path of the blast through the fuel bed.

In testimony whereof I hereto affix my signature.

HARRY F. SMITH.
